UNITED STATES PATENT OFFICE.

FRANK E. VAN TILBURG, OF MINNEAPOLIS, MINNESOTA.

APPARATUS FOR SEPARATING COMPOSITE OILS INTO COMPONENT PARTS.

Application filed June 14, 1923. Serial No. 645,262.

To all whom it may concern:

Be it known that I, FRANK E. VAN TILBURG, a citizen of the United States, residing at Minneapolis, in the county of Hennepin and State of Minnesota, have invented certain new and useful Improvements in Apparatus for Separating Composite Oils into Component Parts, of which the following is a specification.

10 My invention relates to apparatus for separating composite oils into component parts. More particularly, it relates to separating the lighter petroleum products from the heavier petroleum products of crude oil.

15 The objects of the invention are to increase the yield of gasoline or lighter products and to reduce the fuel consumption required for the operation. The invention is based on the principle that a petroleum distillate 20 when once separated from the original mass of crude oil should not again be mixed with a heavier distillate or be allowed to mix with the original mass for the reason that it requires less heat to re-distill the light distillates when not mixed with heavier distillates than it requires when the lighter distillates are allowed to flow back into the still to mix with the original mass and be re-distilled when the mass reaches a higher 25 temperature. The invention is also based upon the well known fact that when there is only a comparatively small difference in temperature between the initial boiling point and the end point of the distillate, it 30 is possible to recover a larger percentage of light petroleum product or obtain an increased yield of products of what is known as low end points or low boiling points such as gasoline and naphtha. By "end point" is 35 meant that characteristic of a so-called distillate which indicates the temperature at which the last of any particular sample is carried off in gaseous form. The general refinery practice has been to re-run the lighter 40 distillates recovered from crude oil whose end points are higher than those of gasoline and when this is done, it requires extra fuel to bring the distillates to the temperature required for vaporization. In refineries 45 which employ what is known as the "continuous system" or a battery of stills consisting of two or more, it has been customary to allow the distillates which flow back from the vapor lines of the stills to go into the 50 original mass of oil with the result that these distillates become mixed with the

original mass. It requires greater heat to re-distill them when thus mixed than it does to re-distill them when kept separate. In order to accomplish the objects of my invention, I provide a battery of stills and associated dephlegmators, and pass the condensate which forms in the first dephlegmator to a pan in the second dephlegmator, and from there on through pans in the other dephlegmators and then into an auxiliary still in which the condensate is subjected to the heat of the vapors coming from one or more of the main stills without bringing such vapors into contact with the condensate that is being re-distilled or in contact with the vapors from such condensate. I also provide for passing the vapors from the auxiliary still to one or more of the dephlegmators. Further, I contemplate utilizing the heat from any one of the stills for the re-distillation of the condensate that is allowed to flow back through pans in the dephlegmators to the auxiliary still.

The full objects and advantages of my invention will appear in connection with the detailed description, and the novel features of my inventive idea will be particularly pointed out in the claims.

In the accompanying drawings which illustrate the operation of my invention,—

Fig. 1 is a view partly in vertical section and partly in side elevation showing an apparatus for carrying out my invention. Fig. 2 is a view in vertical section on the line 2—2 of Fig. 3 showing an auxiliary still. Fig. 3 is a horizontal section on the line 3—3 of Fig. 2.

As shown in the drawings, I provide a plurality of stills or boilers 10, 12, 14, 16 and 18 which are placed above fire boxes 20, 22, 24, 26, and 28, respectively, which furnish heat for vaporizing the oils in the stills. The composite oil to be separated is fed into the first still in suitable manner as by means of a pipe 30 and the stills are connected in series by pipes 32, 34, 36, and 38. Pipes 40, 42, 44, and 46 connect the upper portions of the stills 10, 12, 14, and 16 respectively with dephlegmators 48, 50, 52, and 54, these pipes entering the dephlegmators somewhat above the bottoms thereof. From the tops of the dephlegmators, pipes 56, 58, 60 and 62 lead to condensers (not shown) which may be of any suitable or customary type. Associated with the still 18 is an auxiliary still which includes a casing 64 within which

is a tubular structure having upper and lower heads 66 and 68 joined by a plurality of tubes 70 and extending through the heads so as to connect with upper and lower chambers 72 and 74. The chamber 74 is connected by a pipe 76 with the upper portion of the still 18, this pipe having a shutoff cock 78 and also having a number of branch pipes 80 which may be connected to different stills. The pipes 80 are provided with shutoff cocks 82. The upper chamber 72 is connected by a pipe 84 with a pipe 86, one end of the latter being connected with the upper portion of the still 18 and the other end being connected to a condenser (not shown). A shutoff cock 88 is provided in the pipe 86 between its connection with the pipe 84 and the still 18. From the chamber 74 a pipe 90 leads to a customary run-down tank and this pipe is connected by a branch pipe 92 with a pan 94 supported in the upper portion of the still 18. The pipe 92 is provided with a shut off cock 96 and the pipe 90 below its junction with the pipe 92 is provided with a shutoff cock 98. The space surrounding the pipes 70 between the heads 66 and 68 is connected by a pipe 100 with a customary run-down tank, and this pipe is provided with a shutoff cock 102. Extending through the side wall of the auxiliary still casing 64 is a pipe 104 whose inner end portion 106 is bent downwardly so that the extended lower end is located slightly above the head 68. The pipe 104 outside of the casing 64 is downwardly inclined and its extreme end is located in a pan 108 supported in the upper portion of the first still 10. A pipe 110 leads back from the bottom of the dephlegmator 48 into the pan 108. A pipe 112 connects the bottom of the dephlegmator 50 with the pipe 104 and a branch pipe 114 connects the pipe 112 with a pan 116 supported in the upper portion of the still 12. The pipe 114 is provided with a shutoff cock 118, the pipe 112 below its junction with the pipe 114 is provided with a shutoff cock 120, and the pipe 104 beyond its connection with the pipe 112 is provided with a shutoff cock 122. A pipe 124 connects the bottom of the dephlegmator 52 with the pipe 104, and a branch pipe 126 connects the pipe 124 with a pan 128 supported in the upper portion of the still 14. The pipe 126 is provided with a shutoff cock 130, the pipe 124 below its junction with the pipe 126 is provided with a shutoff cock 132, and the pipe 104 beyond its connection with the pipe 124 is provided with a shutoff cock 134. A pipe 136 connects the bottom of the dephlegmator 54 with the pipe 104 and a branch pipe 138 connects the pipe 136 with a pan 140 supported in the upper portion of the still 16. The pipe 138 is provided with a shutoff cock 142, the pipe 136 below its junction with the pipe 138 is provided with a shutoff cock 144, and the pipe 104 beyond its connection with the pipe 136 is provided with a shutoff cock 146. The pans 108, 116, 128, and 140 are connected in series by downwardly inclined pipes 148, 150, 152. Supported in the lower portions of the dephlegmators 48, 50, 52, and 54 are pans 154, 156, 158 and 160, respectively, which are connected in series by pipes 162, 164, and 166 except the pan 160 is connected by a pipe 168 with the space in the auxiliary still casing 64 between the heads 66 and 68. The pipe 46 previously referred to instead of being connected directly to the dephlegmators 54 is connected to a pipe 170 which connects this dephlegmator with the space between the heads 66 and 68 in the auxiliary still. The pan 160 in the dephlegmator 54 is connected by a pipe 172 with the pipe 104 and the pipe 172 is provided with a shutoff cock 174.

The operation and advantages of my invention will be readily understood in connection with the forgoing description. It should be borne in mind that the temperature of the first still is maintained at about 300° F., and that the temperature of the other stills in succession is increased progressively about 75° F. for each succeeding still, and that a corresponding progressive increase in heat is maintained in the associated dephlegmators. When the cock 88 is closed and the cock 78 is open, vapors forming in the still 18 are caused to pass through the pipe 76 and through the tubes 70 in the auxiliary still 64. From the chamber 72 at the top of the still, these vapors pass through pipe 84 and back into the pipe 86 on their way to the condenser. Condensates which form in the dephlegmators are received in the pans 154, 156, 158 and 160 and flow through the connecting pipes 162, 164, 166 and 168 into the space between the heads 66 and 68 in the auxiliary still where these condensates are subjected to the action of the hot vapors rising through tubes 70. The portions of the condensates thus re-distilled pass out through the pipe 170 and into the dephlegmator 54. It is apparent that vapors from other stills besides the still 18 may be passed through the pipes 80 into the auxiliary still 64 before they are delivered to the condenser. Any condensate forming in the pipes 70 will collect in the chamber 74 from which the condensate may pass through the pipe 90 to a run-down tank when the cock 98 is open or through the branch pipe 92 to the pan 94 in the still 18 when the cock 96 is open, and the cock 98 is closed. The condensate collected in the pan 94 will be re-distilled by the heat in the still 18. Condensate forming in the space between the heads 66 and 68 and around the pipes 70 will be allowed to pass through the pipe 100 to a run-down tank when the cock 102 is opened, while if this cock is closed the condensate will collect in 130

the space between the heads and will pass on through the pipe 104 and be delivered to the pan 108 in the first still in case the cocks 122, 134, and 146 are all open. Any condensate which overflows the pans 154, 156, 158 and 160 in the respective dephlegmators will drop to the bottom of the dephlegmator. The condensate in the bottom of the dephlegmator 48 will flow through the pipe 110 into the pan 108. If the cocks 120, 122, 132, 134, 144 and 146 are all open, the condensate in the bottom of the dephlegmators 50, 52, and 54 will flow through the pipe 104 into the pan 108. If the cock 144 is closed and the cock 142 is open, the condensate in the bottom of the dephlegmator 54 will flow through the pipe 138 into the pan 140. At the same time if the condensate is passing into the pipe 104 from the auxiliary still 64 this condensate will continue down the pipe 104 if the cock 146 is open. If now the cock 146 be closed and the cock 144 be opened, the condensate coming down the pipe 104 will pass through the pipe 138 into the pan 140. If the cock 132 is closed and the cock 130 is open, the condensate in the bottom of the dephlegmator 52 will flow through the pipe 126 into the pan 128. At the same time, if any condensate is passing into the pipe 104 from the auxiliary still 64, this condensate will continue down the pipe 104 if the cock 134 is open. If, however, the cock 134 is closed and the cocks 132 and 146 are opened, the condensate coming down the pipe 104 will pass through the pipe 126 into the pan 128. The connections with the dephlegmator 50 may be similarly operated to direct the condensate into the pan 116. Upon opening the cock 174, the condensate in the pan 160 including that which passes thereinto from the pans 154, 156, and 158 instead of passing to the auxiliary still 64 will pass down the pipe 172 into the pipe 104 and thence into the pan 108 in the still 10. By the employment of the auxiliary still 64, I utilize the heat of the vapors for redistilling the condensate. The condensates collect in the pans in the earlier stills and dephlegmators and pass on to pans in succeeding stills and dephlegmators where they are subjected to progressively increasing degrees of heat. The employment of my invention increases the yield of gasoline, saves fuel, and increases the capacity of the plant.

I claim:

1. Apparatus for separating composite oils into component parts comprising a plurality of main stills, dephlegmators connected with said stills, a pan in each of said dephlegmators for collecting condensate formed therein, pipes connecting said pans in series, an auxiliary still, a pipe connecting the last one of said pans with said auxiliary still for conducting the condensate thereinto, means for conducting vapors from one of said main stills into said auxiliary still for redistilling the condensate therein by the heat of said vapors, and means in said auxiliary still for preventing said vapors from coming into contact with said condensate. 70
2. Apparatus for separating composite oils into component parts comprising a plurality of main stills, dephlegmators connected with said stills, a pan in each of said dephlegmators for collecting the condensate formed therein, pipes connecting said pans in series, an auxiliary still, a pipe connecting the last one of said pans with said auxiliary still for conducting condensate thereinto, means for conducting vapors from one of said main stills into said auxiliary still for redistilling the condensate therein by the heat of said vapors, means in said auxiliary still for preventing said vapors from coming into contact with said condensate, and means for conducting the vapors formed in said auxiliary still to the dephlegmator connected with one of said main stills. 75 80 85 90
3. Apparatus for separating composite oils into component parts comprising a plurality of main stills, dephlegmators connected with said stills, a pan in each of said dephlegmators for collecting the condensate formed therein, pipes connecting said pans in series, an auxiliary still, a pipe connecting the last one of said pans with said auxiliary still for conducting condensate thereinto, means for conducting vapors from one of said main stills into said auxiliary still for re-distilling the condensate therein by the heat of said vapors, means in said auxiliary still for preventing said vapors from coming into contact with said condensate, means for conducting the vapors formed in said auxiliary still to the dephlegmator connected with one of said main stills, and means for conducting reflux condensate from said auxiliary still to one of said main stills. 95 100 105 110
4. Apparatus for separating composite oils into component parts comprising a plurality of main stills, a pan in the upper portion of each of said main stills, pipes connecting said pans in series, dephlegmators connected with said stills, a pan in each of said dephlegmators for collecting the condensate formed therein, pipes connecting said last-named pans in series, means for trapping back into the pans in said stills overflow from the pans in said dephlegmators, an auxiliary still, a pipe connecting the last one of the pans in said dephlegmators with said auxiliary still for conducting the condensate thereinto, means for conducting vapors from one of said main stills into said auxiliary still for redistilling the condensate therein by the heat of said vapors, means in said auxiliary still for 115 120 125 130

preventing said vapors from coming in contact with said condensate, means for conducting the vapors formed in said auxiliary still to the dephlegmator connected with one 5 of said main stills, and means for conducting reflux condensate from said auxiliary still to the pan in one of said main stills.

5. Apparatus for separating composite oils into component parts comprising a 10 plurality of main stills, a pan in the upper portion of each of said main stills, pipes

connecting said pans in series, dephlegmators connected with said stills, a pan in each of said dephlegmators for collecting the condensate formed therein, pipes connecting said pans in series, and means for trapping back into the pans in said stills overflow from the pans in said dephlegmators. 15

In testimony whereof I hereunto affix my 20 signature.

FRANK E. VAN TILBURG.
